LOWERING CHUTE

Filed June 6, 1928

INVENTOR
FRANK PARDEE.
BY D. Anthony Usina
ATTORNEY

UNITED STATES PATENT OFFICE.

FRANK PARDEE, OF HAZLETON, PENNSYLVANIA, ASSIGNOR TO ANTHRACITE SEPARATOR COMPANY, OF HAZLETON, PENNSYLVANIA, A CORPORATION OF PENNSYLVANIA.

LOWERING CHUTE.

Application filed June 6, 1928. Serial No. 283,212.

This invention relates to lowering chutes suitable for transferring various materials from a higher to a lower level. While not limited thereto, the device shown is particularly well suited for the piling of coal.

Heretofore chutes of this character have been provided with upright supports which in some cases have been tied together with cross bracing. The runways have been supported by various members including brackets secured either to an outer spiral flange carried by uprights or to brackets secured to the uprights themselves.

My present improvement aims to provide a self-supporting runway in which it is unnecessary to utilize uprights and in which all supporting brackets, cross-braces and the like which cause breakage of coal and interfere with the piling are done away with.

The invention will be fully apparent from the following specification when read in connection with the accompanying drawings and the features of novelty will be defined with particularity in the appended claims. In the drawings—

Fig. 1 is a side elevation illustrating a lowering chute embodying my invention;

Fig. 2 is a top plan view thereof;

Fig. 3 is a transverse section on line 3—3 of Fig. 2.

Referring in detail to the drawings, 10 and 12 represent, respectively, outer and inner spirally shaped tubular supporting members. The outer member is conveniently formed of a continuous length of spiral pipe. The outer diameter of the spiral being about four feet. The inner member 12 is similarly of spiral form preferably of pipe bent to the form of a spiral, the diameter of which is approximately two feet. These two spaced spiral pipes form a skeleton to which I secure the segmental plates 14 forming the spiral runway. These plates engage the underside of the outer spiral supporting member 10 and are secured thereto by means of bolts 16. Near their inner edges, the jackets 14 are secured by means of bolts 18 to the upper face of the inner spiral supporting pipe 12.

I provide an outer plate-like spiral flange 20, the lower edge 22 of which engages the upper surface of the spiral runway segments 14. The outer face of the plate 20 engages the inner surface of the spiral supporting member 10 and is secured thereto by means of transversely extending bolts 24.

At their lower extremities, the tubular supporting members 10 and 12 are bent around so as to form base portions as indicated at 26 and 28, respectively, which lie in the same horizontal plane. These base portions are 60 preferably, though not necessarily, integral extensions of the members 10 and 12 and they form a staunch base or foundation for the entire runway structure.

The spiral supporting members 10 and 12 65 are so formed and disposed that as viewed in a section taken radially of the spiral, the member 10 lies in a plane higher than the member 12 so as to support the runway segments 14 in such manner that they extend inwardly and downwardly as clearly indicated in Figs. 1 and 3. The structure described provides a support for a spiral runway which is devoid of vertical upright frame members and also avoids the necessity of using cross-bracing or supporting brackets which interfere with the proper handling of coal or similar easily broken materials. While in the drawings I have illustrated only a trifle over a full turn, it is, of course to be understood 70 that the spiral may be made of greater height by merely increasing the number of turns.

The upright flange 20 may be made of extremely thin sheet steel instead of heavy plate material as used in prior constructions and it 75 is much more easily rolled to the proper spiral shape. This flange is not intended to rigidify the structure but merely to serve as a retaining flange to confine the stream of material travelling along the runway. The 80 tubular or pipe-like members 10 and 12, it will be appreciated, form the sole supporting structure for the runway. The material may be fed to the runway by any suitable means such, for example, as by means of the 85 inclined chute 30 shown in the drawings.

While it seems generally preferable to design the parts of such dimensions as to avoid the necessity of the ordinary supports or braces, yet spiral members of the character 90 above referred to may be used with advantage also in connection with such supports or braces.

While I have described quite specifically 105 the details of the embodiment of the invention illustrated, it is not to be construed that I am limited thereto since various modifications may be made by those skilled in the art without departing from the invention as defined in the appended claims.

What I claim is:

1. A spiral lowering chute comprising a spiral runway supported at its inner and outer edges by separate spaced spiral members, the lower ends of which are extended and disposed in the same plane to form a supporting base for the structure.
2. A spiral lowering chute comprising a spiral runway supported by inner and outer tubular members and an upright spiral plate-like flange having its lower edge engaging the runway and being secured to the outer tubular member.
3. A spiral lowering chute comprising a spiral runway supported by inner and outer tubular members and an upright spiral plate-like flange secured to the outer tubular member.
4. A spiral lowering chute comprising a spiral runway supported at its inner and outer edges by laterally spaced spiral pipes having their lower ends extended and bent into the same horizontal plane to form a supporting base.
5. A spiral lowering chute comprising a spiral runway formed of a series of segmental plates, an outer spiral tubular support to which said segmental plates are secured, an upright spiral plate-like flange secured to said tubular support and a base secured to said tubular support.

6. A spiral lowering chute comprising a spiral runway formed of a series of segmental plates, an outer spiral tubular support to which said segmental plates are secured, an upright spiral plate-like flange secured to said tubular support, and an inner tubular support secured to the segmental plates.

7. A self-supporting spiral runway including inner and outer spiral supporting members having extensions disposed in substantially the same horizontal plane and forming a supporting base for the structure.

8. A self-supporting spiral lowering chute comprising inner and outer spiral supporting members having integral base portions, a runway comprising a series of segmental plates secured at their inner and outer portions to said members and an upright flange secured to one of said members.

9. A self-supporting spiral lowering chute comprising inner and outer spiral supporting members having base portions, a runway comprising a series of segmental plates secured at their inner and outer portions to said members and an upright spiral plate having its lower edge engaging the runway and being secured to the inner face of the outer spiral supporting member.

In witness whereof, I have hereunto signed my name.

FRANK PARDEE.
